COMBINATION CONTAINER FOR PILLS AND WATER

Florabel Maben, Visalia, Calif.
(3632 Park Blvd., Apt. E, San Diego, Calif. 92103)

Filed Mar. 26, 1969, Ser. No. 16,466

Term of patent 14 years

Int. Cl. D9—04

U.S. Cl. D9—185

Fig. 1.

Fig. 2.

Fig. 3.

Fig. 4.

Fig. 5.

I claim:

The ornamental design for a combination container for pills and water, as shown.
